[57] CLAIM

The ornamental design for a hammer handle, as shown and described.

DESCRIPTION

FIG. 1 is a perspective view of a hammer handle showing my new design;

FIG. 2 is a bottom plan view thereof;

FIG. 3 is a top plan view thereof;

FIG. 4 is a right side elevational view thereof;

FIG. 5 is a rear elevational view thereof; and,

FIG. 6 is a front elevational view thereof.

The left side of the hammer handle is a mirror image of the right side.

The hammer head and grip shown in broken lines in FIGS. 1-6 are not part of the claimed design.
